UNITED STATES PATENT OFFICE.

ALBERT G. THOMAS, OF LYNCHBURG, VIRGINIA.

VACUUM OR THERMIONIC TUBE.

Application filed August 2, 1923. Serial No. 655,318.

This invention relates to new and useful constructions and dispositions of the elements of vacuum or thermionic tubes such as are used in wireless communication, and 5 to the circuit systems used with such tubes.

One of the objects of this invention is to reduce the cross-section and increase the concentration of the grid-filament field and of the electronic stream at or near the point of 10 action of the grid. Another object is to attain this reduction and concentration by mechanical construction of the elements and by disposition of suitable sources of electrical energy. Further objects are to provide 15 cathodes of larger emissive area, and to dispose the grid out of the direct trajectory of the electrons passing to the plate, so it no longer is an obstacle to the passage of some of the electrons.

With these and other objects in view, as will appear in the following specifications, I have represented some exemplifications of the construction of such tubes in the accompanying drawings, in which:

Fig. 1 is a diagrammatic presentation of a tube with a related circuit;

Fig. 2 is a similar view of a modified tube, with a related circuit;

Fig. 3 is a further modification, with a related circuit;

Fig. 4 shows a modification of the tube of Fig. 1.

In all of these figures, F represents the filament of tungsten, thoriated platinum, or the like. G is the grid or controlling member, and P is the plate or receiving member. 1 indicates the evacuated glass tube or vessel for containing the several elements. A is the battery for heating the filament F, and R is the corresponding regulating rheostat. The antenna circuit in each case comprises the antenna 8, the series condenser C', inductance L', and the ground 11. The secondary circuit comprises the inductance L² in variable electromagnetic relation with L', and a tuning condenser C²; a grid leak 14 and grid condenser 15 have the customary place and functions. The telephone or other indicator of received and detected signals is designated by T, and the battery for furnishing the filament-plate current and rendering the plate positive with regard to the filament at B. The various elements are shown diagrammatically, and in practice

may be supported and retained within the vessel 1 in any appropriate manner.

In Fig. 1, is shown a tube having a filament F which may be in a straight line as shown, or wound spirally to conform to the shape of the element F' disposed about it; since its object is to heat the element F' by radiation and bombardment, the particular shape is unimportant. Surrounding and coaxial with the filament F is a cylindrical or Venturi-tube shaped element F' of uniform thickness, which forms the emissive cathode proper. It is shown as shaped as a figure of revolution, i. e., like a Venturi tube or a pulley, with an external groove having a circular section, with the center of this circle at the interstice between the grid rings G. It is preferably coated on the outside, or the side next the grid elements, with sodium, thorium or other easily ionizable material. The grids G are two dished rings coaxial with the filament F and element F', and disposed at a distance apart slightly greater than the thickness of the electronic stream. The plate is formed as a cylinder P coaxial with the filament F, and may be Venturi-shaped to correspond to element F'. The circuit connections are as usual, with the addition of the battery B', between filament and cathode F', to make the filament negative with regard to the cathode. The heating of the cathode F' determines an emission of electrons, which tend to depart in a direction normal to the surface, and thus to pass through the interstice between the grid rings G. The small area and size of the grid members entails a high concentration of the charge upon them with a consequent strong field, and thus a great amplification of the signal. It should be especially noted that the grids G are entirely out of the trajectory of the electronic stream, and therefore do not form a physical obstacle to the passage of the stream.

In Fig. 2, the filament F is rebent and curved to occupy a spherical surface concentric to F', to enable the filament F to have the greatest effect upon F'. The cathode F' is here formed as a curved reflector, preferably spherical, focussed or centered upon a spot O; a battery B' or other source keeps F negative with respect to F' and the electronic stream leaves the reflector normal to its surface and therefore passes through a

focus at O. Disposed about this spot O as its geometrical center, or nearly so, is a small cylindrical grid G. The plate P is a spherical surface similar to F', and likewise is centered about O; preferably it projects very little beyond the area struck by the cone of electrons passing through the grid. As before, the material of which G is composed may be any, as strips, mesh, etc.

10. The operation of Fig. 2 is similar to that of Fig. 1. The principal difference in the two figures is that here the electrons are focussed at a point; while in Fig. 1 they are focussed at a circular line between the grids.

15. The dotted lines indicate paths of electrons passing from cathode to plate.

Fig. 3 has the filament F disposed next to the grid which is formed as a hollow surface G such as a cylinder or toroid on either side of the focus of the filament F, which is rebent and curved to cylindrical shape. Behind the filament F is disposed a cylindrical reflector S of metal, which is charged to a high negative potential with regard to the filament by a battery B'. In the drawings, the reflector S and filament F have been conventionally shown as having cross sections in the form of circular arcs: but it will be understood that the length of the cylinders in each instance may be determined by the designer according to the known rules of active surface requirements, etc. This reflector causes the electrons emitted from the filament to move in directions normal to the cylinders F and S and radial to the focus O, and prevents the emission of electrons in a direction opposite to that from filament to grid. The plate P is either plane or cylindrical about O as a center and is constructed of such size as not to extend appreciably beyond the area enclosed by the lines of the grid. Here again the grid-filament electrostatic field is very much concentrated at O, and a great proportional change in the plate-filament current occurs. The filament is preferably made of ribbon shaped material.

Fig. 4 shows a tube similar to that in Fig. 1, but has the filament itself curled into a spiral of the shape indicated for the cathode F' of Fig. 1. It therefore itself both emits the electrons and directs them normal to its general bounding surface. The grids G, G are formed as two parallel rings separated by an interstice of such width that the converging electrons are afforded unobstructed passage from the filament F to the plate P, which in this case has plane or curved surface.

60. The circuits shown are appropriate for use with these tubes, although any present

circuit may be used therewith with some success after the inserting of a polarizing battery across filament and cathode.

What I claim is:

1. In an electron discharge tube, a cathode having its outer surface as a figure of revolution generated by the movement of an arc about an axis of symmetry within the cathode, said axis being on the convex side of said arc and in its plane whereby electrons emitted in paths normal to said surface converge upon a circle having its center at said axis.

2. In an electron discharge tube, a filament, a hollow cathode of circular cross section concentric with said filament, said cathode having its outer surface of arcuate section in a plane passing through the filament, said surface being directed away from said filament, a circular grid structure concentric with said filament and cathode and located adjacent the center of curvature of said cathode section, and an anode.

3. In an electron discharge tube, a cathode having the external form of a figure of revolution generated by the revolution of a circular arc about a line in the plane of the arc and on the side thereof opposite its center, two grid rings of the diameter of and located adjacent and parallel to and coaxial with the imaginary circle traversed by the center of the circle of the arc whereby the rings present an opening for the passage of electrons emitted in a focused stream from said cathode, and an anode.

4. In an electron discharge tube, a cathode adapted to emit electrons, said cathode having its external surface formed as a figure of revolution generated by an arcuate line moving about an axis on the convex side of the arcuate line, so that the emitted electrons are focused upon a circle, grid rings disposed parallel to the said circle, and an anode.

5. In an electron discharge tube, a cathode having a surface adapted to emit electrons, said surface being a figure of revolution generated by the movement of an arc about an axis lying in its own plane and on the convex side of the arc whereby electrons emitted in paths normal to the said surface converge upon a circle concentric with said cathode, two circular grid rings disposed parallel to said circle, and an anode.

6. In an electron discharge tube, a cathode having the external form of a figure of revolution generated by the revolution of an arc about a line in the plane of and on the convex side of the arc.

In testimony whereof I affix my signature.

ALBERT G. THOMAS.
